(57) **CLAIM**

The ornamental design for a transparent cigarette lighter case, as shown and described.

DESCRIPTION

FIG. 1 is a perspective view of the transparent cigarette lighter case showing the new design.

FIG. 2 is a front elevational view thereof.

FIG. 3 is a side elevational view thereof.

FIG. 4 is a top plan view thereof; and,

FIG. 5 is a front elevational view showing the interior design of the case viewable through the transparent cover.

The key ring has been omitted from the disclosure of FIG. 5 for convenience of illustration.
